CLAIM

The ornamental design for a filter cartridge, as shown and described.

DESCRIPTION

FIG. 1 is a perspective view of a filter cartridge showing the new ornamental design, the portions shown in broken lines forming no part of the design sought to be patented;

FIG. 2 is a front view thereof, the front and rear views being a mirror image, and the portions shown in broken lines forming no part of the design sought to be patented;

FIG. 3 is a left side elevational view thereof, the left and right views being a mirror image, and the portions shown in broken lines forming no part of the design sought to be patented;

FIG. 4 is a top plan view thereof; and,

FIG. 5 is a bottom plan view thereof.
